UNITED STATES PATENT OFFICE

2,650,795

BED LIFTER

Alfred B. Bell, Philadelphia, Pa.

Application June 2, 1950, Serial No. 165,837

10 Claims. (Cl. 254—100)

1

This invention has general reference to portable lifting devices useful for elevating the ends of articles of furniture to facilitate cleaning the supporting surface thereunder.

More particularly my invention has for a primary object to provide an improved type of bed-lifter characterized by structural refinements whereby said lifter may be used with assurance that the bed is positively restrained against movement tending to release the lifter therefrom. In other words, when the lifter is in active position with the bed elevated at one end, said bed in addition to the lifter is effectively kept stationary.

Another object of my invention is to provide a portable bed-lifter which can be easily applied to and released from a bed end with a minimum of physical effort.

A further object of my invention is to provide a bed-lifter that is simple in construction, comparatively cheap to manufacture, and very durable in character.

A still further object of my invention is to provide a device of the type above indicated which will be extremely useful in sick rooms and similar places where it is desirable that the foot or head end of a bed be raised for relief of those suffering from cardiac trouble or other ailments necessitating inclination of the body for comfortable repose.

With the foregoing and other objects, as well as ancillary advantages, in view which will hereinafter appear as the nature of my invention is fully described; said invention essentially consists in the novel features of construction and combination of parts, illustrated by the accompanying two sheets of drawings, and more particularly defined in the claims.

In the drawings:

Fig. 1 is a broken elevational view of a typical embodiment of my improved lifter device with a fragmentary portion, at the upper left-hand of said figure, in section to better show otherwise obscured structural features.

Fig. 2 is a side elevation of Fig. 1, as viewed looking from the right toward the left-hand of said figure and as initially applied to a bed end, prior to elevating the latter, with the actuator-handle omitted.

Fig. 3 is a similar view to the preceding but showing the bed end elevated by the lifter, and the latter inclined over from the vertical incidental to elevation of one end of the bed.

Fig. 4 is a broken elevation and part sectional view of the lower and upper sections of the lifter drawn to larger scale, and with the handle part of the actuator omitted to compact the illustration.

Fig. 5 is a fragmentary elevation taken as indicated by the angled arrows V—V at the upper left-hand of Fig. 4.

Fig. 6 is a broken plan action taken approxi-

2

mately as indicated by the angled arrows VI—VI in the lower part of Fig. 1, but drawn to larger scale for clearer illustration of important details.

5 Figs. 7, 8 and 9 are cross-sections respectively taken as indicated by the angled-arrows VII—VII, VIII—VIII and IX—IX in Fig. 1.

Fig. 10 is a fragmentary plan section taken as indicated by the staggered dot-and-dash line X—X in Fig. 6; and

Fig. 11 is an enlarged detail section showing how the base parts of the elevator device are connected together.

In the drawings herewith like characters of reference are applied to corresponding parts in all the views, and in the descriptive matter specific terms are employed for the sake of clarity; but it is to be understood that the scope of my invention is not thereby limited; each such term being intended to embrace all equivalents which perform the same function for an analogous purpose.

Referring to the drawings more in detail, the lifter-device of this invention comprises a base 25 which I conveniently and comprehensively term a triangulate stand 11. This stand 11 is conveniently, although not necessarily, made of seamless steel tubing of appropriate diameter and gage to include a center post 12, opposingly

30 inclined branches 13 merging into spaced extensions 14, and axially aligned braces 15. By way of example only, the center post 12 may be of one-inch tubing, the branches 13 and extensions 14 of seven-eighths inch tubing and the braces 35 15 of three-quarter inch tubing. It is to be noted, however, that the upper ends of the inclined branches 13 are appropriately shaped for abutment against the center post 12 and integrated thereto by surrounding fillet-welds as

40 typically indicated at 16, Figs. 1 and 4. In like manner the braces 15 are united to the center post 12 and branch extensions 14 by similar welds 17, 18, respectively. The tubular center post 12, as well as the free ends of the branch

45 extensions 14 are, respectively, equipped with semi-spherical concavo-convex section socket caps 19, 20 integrated, or otherwise rigidly secured, to said post 12 and extensions 14 by welds 21, in an obvious manner. Other means such as

50 hard-rubber, or ball casters may be substituted for the socket caps 19, 20 without departing from the scope of my invention; but it is to be particularly remarked that the lower outer surface of the center-post socket cap 19, see Figs. 1 and

55 2, normally, never contacts the supporting surface or floor 22 on which the stand 11 seats, for a reason hereinafter explained.

Supported by and movable relative to the triangulate stand 11 is the elevator device or means comprehensively designated 23. This elevator device or means 23 comprises a main element or plate component 24, preferably of the cross-sec-

tion best understood from Figs. 6-9 inclusive; said component being suitably shaped to embody a back or rigid component 25 including spaced ribs 26 and side flanges 27, with the latter retroverted inwards at 28 to define parallel grooves 29, for snug reception of the outwardly directed flanged edges 30 of a member 31. This member 31 is of somewhat channel section, see Figs. 7 and 9 to best advantage, with the web portion 32 suitably depressed to arcuate section, for a purpose hereinafter set forth; whereas the side portions 33 are opposingly depressed at 34, Figs. 1-4, at the location of a follower nut 45, hereinafter further explained.

Rotatable in the center post 12 is a vertical shaft 36 embodying a plain or lower section 37 for seating in the bore 38 of said post and it is held in place by a set-screw 39 engaged in a lateral and interiorly-threaded socket 40, provided for the purpose, on the post 12; whereas said set-screw 39 preferably has the inner end tapered at 41 for coaction with a complementally sectioned groove 42 in the lower section 37 of the shaft 36, see Fig. 9, to best advantage. The shaft 36 also includes an intermediate screw-threaded section 43, for operative coaction with the correspondingly threaded bore 44 of a multi-sided follower-nut 45, later on herein again referred to; as well as an upper or co-axial diametrically-reduced smooth extension 46. Freely fitting the extension 46, between the screw-threaded section 43 is a tubular hand-grasp 47 which may have the exterior surface milled, or otherwise fashioned for grippage by the user's one hand; while said grasp 47 is prevented from lengthwise displacement by aid of a retainer collar 48 secured in place by a screw 49, in an obvious manner. As best shown by Figs. 4 and 5 the shaft reduced extension 46 is axially drilled to provide a bore 50, while it is longitudinally slotted at 51 for reception of the downwardly-angled stem portion 52 of an actuator 53, Fig. 1; whereas said stem 53 is restrained against turning movement relative to the shaft 36, by aid of that portion, outwardly relative to the stem 52, engaging in the longitudinal slot 51. The actuator 53 is prevented from accidental removal, from the bore 53, by means of a cap-screw 54 threaded in the outer end of the shaft bore 50, as readily understood by those conversant with the art. The outer end of the actuator 53 is conveniently bent upwards at 55, Fig. 1, and is equipped with a freely rotative grasp or handle 56, for operating the lifter or elevator means 23 as hereinafter described.

Referring back again to the follower-nut 45, see Figs. 1 to 4 and 8, the same has integrated thereto as by welds 57, what I preferably term a carriage-guide 58, the same consisting of a rigid metal strip having the respective ends provided with guide eyes or loops 59, through which are guided the parallel legs 60 of an U-shaped elongate stabilizer unit 61, conveniently of half-inch diameter seamless metal tubing, with the free ends closed-in by cap-screws 62; whereas the medial portion of the bend 63 is integrated to the stand center-post 12 at 64, see Fig. 1; and also to the parallel legs 60 of the unit 61 at 64', see Fig. 1. In addition to the foregoing described means the movement of the carriage member 31 may be further stabilized by providing one or more inverted U-shaped guide straps 65, see Figs. 1-3, with clearance over the threaded-section 43 of the shaft 36, which may be formed with said member 31, or be integrated thereto, as

readily understood more particularly on examination of Fig. 7. It is observable the strap 65 affords a regional clearance 65' around the shaft threaded section 43 to enable slight angular self-adjustment of the carriage member 31, with respect to the plane of the stand 11 as the latter inclines away from, and to, the vertical during elevation of the lifter device.

Attention is now directed to the provision of the follower nut 45 with axially aligned stepped bearing-pins 66 the diametrically largest portions 67 whereof about opposed walls of said nut to afford fulcrum connection for the complementally apertured ends of carriage supports or braces 68 conveniently of half-round edged bar-stock, for example only. The braces 68 are preferably sheathed with resilient material tubing 68' to prevent said braces from damaging surfaces with which they may come in contact. Each brace 68 has its lower end integrated at 69 to the vertical portion 10 of an angle-section foot-plate 71, see Figs. 2, 3, 6 and 10, more particularly, whereas the horizontal portion 72 of said foot-plate 71 is equipped with a non-slip tread 73, while it also affords support for an underlying laterally adjustable retainer element 74 having one edge portion flanged at 75, with its upper edge curved outwards at 76, for a purpose later on herein clarified. Adjustment of the retainer element 74 relative to the foot-plate 71 is attained by equipping said plate 71 with individual holes 77 for variable registration with serially spaced holes 78 in the retainer element 74, and passage therethrough of clamp-bolts 79 in an obvious manner. It is also to be understood that the tread 73 is furnished with holes 80 for passage of the bolt-heads 79' into engagement with the foot-plate 71, when the clamp nuts 81 thereon are tightened-up, and all of which will be clearly apparent to those conversant with the related arts.

Referring again to the bearing pins 66 it is to be observed that the intermediate sections 82 thereof engage in, or fulcrum between, the bearing brackets 35, hereinbefore described; whereas the smaller diameter portions 83 of said pins are fitted with lock washers 84, against which the outboard ends of the pins 66 are "peened" or riveted at 85 for maintenance of the parts 66, 35, 68 and 45 in assembly. 86, Figs. 2, 3 and 6-10 inclusive, designates a felt or other suitable material protective pad cemented to the back of the lifter component 24 that serves to prevent marking or otherwise damaging the confronting bed end 87, Figs. 2 and 3.

Having described the structural features of my invention it will be readily understood that to sufficiently raise the foot-board end 87 of any old style or modern type of bed, relative to the supporting surface or floor 22, the head end of such bed should be firstly drawn away from the adjacent wall about ten to twelve inches, whereupon the padded foot-plate 71, 74 is pushed under approximately the central portion of foot-board end 87, with the flange 75 clearing the inside face of the said end 87 as clearly shown in Figs. 2 and 3. Particular attention is directed, at this juncture, to the fact that the socket cap 19 of the center part 12 at all times is clear of the floor 22, whereby the rigidity of the stand 11 with the lifter device 23, as a unit, is positively maintained and lateral movement thereof relative to the bed end 87 or floor 22 is prevented. The operator or user of the lifter device 23 next grips the grasp 47 with either hand and turns the actuator 53

clockwise with the other hand, whereupon the non-slip tread 73 is brought upwardly into engagement with the lower edge of the foot-board 87. Continued rotation of the actuator 53 will thereupon, obviously, effect elevation of the bed 87 to the desirable extent for the cleaner to not only see under the bed but enable much more expeditious movement of the floor cleaning equipment. On the other hand when the floor cleaning operation has been completed, the lifter-device of my invention is just as promptly released by the simple expedient of reversing rotation of the actuator 53, or by turning the latter in a counter-clockwise direction.

From the foregoing disclosure it is felt the merits and advantages of my invention will be clearly understood, and while I have described in detail one practical embodiment of said invention, the same is not to be construed as limitative, inasmuch as the lifter device may be substantially an all steel set up, with the screws, bolts and nuts of dissimilar material; or of wood and steel construction, without departing from the spirit and scope of my invention as more particularly defined in the following claims.

Having thus described my invention, I claim:

1. In a device of the type described, a triangulate stand including a hollow center-post with opposingly inclined branches embodying angularly-related portions merging into spaced extensions; axially aligned braces rigidly connecting said extensions to the center-post, and a caster element secured to the free end of each such extension for point contact with the device supporting surface; elevator means mounted to the triangulate stand including a rigid component and a lifter-component movable relative thereto, as well as having joint capacity for slight angular self-adjustment with respect to the plane of the stand aforesaid; a foot-piece at the lower end of the lifter-component for projection below an article of furniture, to be inclined to the horizontal at times, for easy access thereunder; an operating shaft, socketed and turnably restrained in the base center-post with a reduced extension thereabove, and said shaft also embodying a screw-threaded section and a lower plain section; a follower on the operating shaft screw-threaded section having axially aligned bearing-pins; apertured brackets projecting from the lifter-component for reception of the follower bearing pins, and said follower also including spaced guide eyes; a stabilizer unit embodying parallel portions engaged through the guide eyes, and said unit being rigidly secured to the center-post and inclined branches of the triangulate stand; and actuator mechanism carried by the operating shaft, outwardly of its screw-threaded section, whereby said shaft is rotatable to effect inclined elevation of an article of furniture relative to its supporting surface and return thereto.

2. The invention of claim 1 wherein the lifter-component foot-piece is preferably in the form of an angle-section plate; and wherein the furniture engageable portion of said plate, as well as the article of furniture confronting parts of the lifter device, are equipped with durable resilient material, effective to prevent defacement or damage to the contacting portions of said article of furniture.

3. The invention of claim 1 wherein the triangulate center-post, as well as both inclined branch extension lower end castor elements, are preferably in the form of semi-spherical con-

cavo-convex socket-caps; and wherein the center-post socket-cap is positioned at a level to clear the supporting surface when the lifter-device is in use.

5. The invention of claim 1 wherein the elevator rigid-component is in the form of a plate embodying spaced ribs and side flanges, with the latter lengthwise retroverted to define parallel grooves, and wherein said rigid-component also

10 includes apertured bearing elements; wherein the relatively movable component is of channel-section with the web portion inwardly depressed to arcuate formation for partial reception of the operating-shaft screw-threaded section; wherein the side flanges of said movable-component are outwardly angled along their free edges for slideable engagement in the rigid component parallel grooves; and wherein said side flanges are opposingly depressed intermediate their ends.

15 20 25 5. The invention of claim 1, wherein the follower is in the form of a multi-sided nut; wherein the axially-aligned bearing-pins project from opposed faces of said nut and are stepped outwardly; and wherein the outer ends of said pins are equipped with attaching means, for the purpose specified.

6. The invention of claim 1, wherein the operating-shaft reduced extension is axially bored and includes a longitudinal slot for reception of an angled actuator member; and wherein the free end portion of said extension bore is threaded for reception of a cap-screw effective to normally prevent accidental separation of the parts aforesaid.

30 35 40 7. The invention of claim 1 further including a sleeve freely mounted on the operating shaft reduced extension, intermediate the screw-threaded section and a retainer collar made fast to said extension upper portion; and wherein the outer surface of said sleeve is suitably roughened to serve as a hand-grasp.

8. The invention of claim 1, wherein the stabilizer unit consists of a U-shaped tube with its leg portions slideable through the follower guide-eyes and their free ends closed-in by cap-screws; and wherein the medial portion of said U-shaped tube, as well as opposed parts of legs are, respectively, integrated to the triangulate stand center post and the opposingly inclined branches of said post.

45 50 55 9. The invention of claim 1, wherein the foot-piece of the lifter-component comprises an angle-section plate and a relatively adjustable retainer-plate; and wherein said retainer-plate embodies an upwardly directed flange having the free edge thereof outwardly curved.

10. The invention of claim 1 further including means effective to positively restrain the operating-shaft from lengthwise displacement; said 60 means comprising an interiorly-threaded radial projection from the triangulate-stand center-post; and a set-screw in said projection having its inner end tapered for coaction with a groove in the lower section of the operating shaft aforesaid.
